UNITED STATES PATENT OFFICE.

CARL DENZLER, OF DETROIT, MICHIGAN.

LOCK.

1,021,864.

Specification of Letters Patent.

Patented Apr. 2, 1912.

Application filed January 27, 1911. Serial No. 604,950.

To all whom it may concern:

Be it known that I, CARL DENZLER, a citizen of Switzerland, residing at Detroit, in the county of Wayne and State of Michigan, have invented certain new and useful Improvements in Locks, of which the following is a specification, reference being had therein to the accompanying drawings.

This invention relates to door-locks, and 10 it has for one of its objects the provision of a device of the character, in which the latch bolt is normally held against withdrawal movement in a positive manner.

The invention has, furthermore, for its 15 object the provision of a combined latch and lock-bolt in combination with means for locking the same against withdrawal in such a manner that for ordinary use a push or pull of the knob member in the direction in 20 which the door is to be swung will permit the latch-bolt to be withdrawn by a spring; while, on the other hand such release is positively prevented.

Other objects of the invention will hereinafter appear, and their means of attainment will be specified in the claims.

The invention has been clearly illustrated in the accompanying drawings, in which similar characters denote similar parts and 30 in which—

Figure 1 represents a horizontal section through the swinging end of a door, with its lock and also a portion of the joint, all in closed position but set for ordinary use, viz: 35 without a key; Fig. 2 is a vertical section on line 2—2 of Fig. 1; Fig. 3 is a similar section on line 3—3 of Fig. 1; Fig. 4 represents a vertical section through the door, the lock, and the jamb, on line 4—4 of Fig. 40 1, and Fig. 5 is a perspective view of the outer push-member of the lock.

Briefly stated, my improved lock comprises a bolt which serves at the same time for a latch and also security-bolt, and which 45 is normally held in its locked position in a positive manner by a slide which is operable by a plunger connected with the door-knob. The bolt is normally thrown inward, that is: out of engagement with the keeper, by a 50 spring whenever the slide is in position to permit such action. In fact the slide member is the controlling feature of the device, as upon its movement depends the operation of the bolt. This slide may also be locked 55 against longitudinal movement by a catch operable from the "inside" face of the door,

so that the latter cannot be opened either from outside or inside. In order to permit the door to be locked from the outside so that a key may be used, the slide is mounted 60 for rotation thereby, to present a plain surface to the lock bolt to rest against, and the movement of the outside plunger will then have no effect on the position of the lock-bolt in the keeper, in which case the key 65 must be used again to reopen the door from the outside without however presenting any obstacle to the door being opened from the inside by turning and pulling the knob. Again, the catch may be operated to prevent the slide being moved in any way, in 70 which case the door cannot be opened either from outside or the inside.

Referring to the drawings, the door-casing or jamb J has a keeper 10 provided with 75 a perforation 11 to receive the lock-bolt of the door. The door D is mortised to receive the lock which comprises a stationary inside plate 12 the flange 12' of which may be rigidly secured to the door in any desired manner. The central portion of the plate has a rearwardly extending tubular projection 13 within which the controlling member of the lock is mounted for rotation as well as for longitudinal movements. A lock-bolt 14 is mounted for movement transversely to the axis of the extension 13, and is guided at its inner end in a cylindrical boss 15 of said extension; while its outer end is guided in a cylindrical lug 16 of the 80 face plate 17, both lug 16 and boss 15 being preferably connected by a tube 18. As above stated, the lock-bolt is normally withdrawn from the keeper, as for instance, by a spring 19 interposed between the face of the lug 16 and a collar 20 on the bolt. The inward movement of the latter is controlled by a member mounted for rotative and also sliding movements in the extension 13, and which comprises a cylindrical body 21 which is cut-away at 22 to form a cam face 23, so 85 that when the body 21 is moved in the direction of arrow a (Fig. 1) the lock-bolt 14 may move inward and out of engagement with the keeper 10. A spring 24 surrounds the stem 25 of the controller and serves normally to place the body 21 into the position shown in Fig. 1, by virtue of its strength being superior to that of the bolt-spring 19. This "outward" movement of the controller 90 may be limited by a key-screw 26 secured on the "inside" knob 27 and entering a col- 95

lar 28 which is loose on the stem and rests against a set-collar 29 in the stem 25. It will therefore be seen that when a pull is exerted on the knob 27, the body 21 will be 5 pulled forward against the action of the spring 24 and the bolt 14 will therefore be permitted to move inwardly by the force of the spring 19 and thus finally clear the keeper 10. Now, inasmuch as the knob has 10 thus been pulled away from the door-plate 12, it follows that as soon as the bolt 14 is clear of the keeper 10, the door will follow the knob 27, the notch 22 being maintained in position against rotation opposite the lock 15 bolt 14 by the inner end 30' of a catch member 30 riding in a longitudinal groove 31 formed in the body 21.

Secured to the "outside" of the door D, is a hand-knob 35 in axial alinement with 20 the controller and the extension 13 of the inner plate 12, both parts being positively interlocked against rotative movement relative to each other by wings 36 (see also Fig. 3) formed on the extension 13 and entering 25 grooves 37 in the outer knob-member 35.

Means are provided for longitudinally moving the controller from the "outside" of the door, these means consisting of a chambered plunger 40 which is guided in 30 the knob 35 and the extension 13, the inner end of said plunger abutting against the outer end of the body 21, which is provided on its abutment face with a plurality of radial ribs 41 adapted to engage V shaped 35 grooves 42 in the abutment face of the plunger, for purposes to be hereinafter described. In order to prevent the plunger from being 40 rotated and yet be longitudinally movable, it is provided with a pair of diametrically opposite wings 43 (see also Fig. 5) slidable in grooves 44 in the knob 35, as limited by a sleeve-collar 45 in screwthreaded engagement with the latter.

Under ordinary conditions the outer knob 45 could be removed together with the plunger, and in order to prevent tampering with the lock mechanism, the controller comprises an "outwardly" extending stem 47 passing through the inward end of the plunger, and 50 provided with a screw-collar 48 movable within the chamber of the plunger. Removal of the knob 35 as well as of the plunger 40 is therefore prevented from the "outside" of the door, through the set collar 29 (on the 55 inward end of the controller), the intermediate collar 28, the inner door-plate 12, the controller with its collar connections 29 and 48, the wings 43 and screw sleeve 45.

In the combination shown in Fig. 1, the 60 door may be opened by an inward pull on the knob 27, or by an inward push on the plunger 40. When it is now desired to secure the door against unauthorized intrusion, it will only be necessary to lock the controller against longitudinal movement and

thus prevent the lock-bolt from moving inward. The catch-device 30 answers this purpose. Since the groove 31 is normally in longitudinal alinement with the catch 30, I deem it preferable to rotate the controller 70 in the direction of the arrow b (see Fig. 1), a groove 50 (see Figs. 1 and 4) being provided to permit such rotation for about ninety degrees, which will bring the groove 31 out of alinement with the catch 30, and at the same time present a plain surface to the inner end of the lock-bolt 14. The groove 50 has a stop-face 51 and a deeper recess 52 into which latter the catch 30 may be forced against the action of a spring 53, 80 which normally maintains said catch in the position shown in Fig. 1, and is seated in a recess 54 of the door-plate extension 13. This inward movement of the catch is effected by a hand-operated lever 55 secured on a spindle 55 which is journaled in the door plate 13 and carries a cam 56 (see Fig. 4) having flat sides whereby the spring-pressure on the catch 30 will hold the cam in its position either to force the catch 30' 90 into the deep recess 52 or else as illustrated, under which conditions the door may be locked from the "outside" by a key such as K, which may have any particular characteristics as to its fitting the controller, the 95 present form comprising a pair of pins K' adapted to enter corresponding recesses K" in the controller. It is just in connection with this turning movement of the controller that the ribs 41 and plunger-notches 100 42 come into play, because they will yieldingly hold the controller against accidental rotation relatively to the non-rotatable plunger 40. A person leaving the house can therefore use a key to "lock the door," 105 and it will require a key from the outside, or else a partial rotation of the inside knob to reopen the door, the "inside" knob being interlocked for rotation with the controller by the end of the knob-screw 26 entering a 110 slot 57 in the controller-stem 25. When it is desired to "lock the door" against being opened by any means whatever, from inside as well as outside, the handle 55' is swung to force the pin-end 30' into the deep recess 52 of the plunger. Normally the inner end of the lock-bolt is in slight surface contact with the inclined face 23 so that the door, when open, may be closed by force, the outer end of the bolt riding along the 115 face of the keeper 10, and thus cam the controller "inward."

Many changes may be made in the particular construction and organization of the elements composing my improved lock, 125 without departing from the spirit of the invention.

I claim:

1. The combination with a normally-retracted lock-bolt, of a rotatable controller 130

therefor comprising a body for maintaining said bolt in its projected position, said body having a recess adapted to be brought into register with said bolt to permit the retraction thereof, and a knob for moving said controller, and means for locking said controller against rotation.

2. The combination with a normally-retracted lock-bolt, of a longitudinally movable and rotatable controller therefor comprising a body for maintaining said bolt in its projected position, said body having intermediate its ends a recess adapted to be brought into register with said bolt from either direction to permit the retraction thereof, and a knob for moving said controller, and means for locking said controller against longitudinal movement and against rotation.

20 3. The combination with a normally-retracted lock-bolt, of a movable controller therefor comprising a body for maintaining said bolt in its projected position, said body having intermediate its ends a recess adapted to be brought into register with said bolt from either direction to permit the retraction thereof, and a knob for moving said controller, a hand-operable catch for locking said controller against movement and comprising a slip-bolt, a spring for withdrawing said slip-bolt, and a cam for bringing said slip-bolt into lock-engagement with the controller.

4. The combination with a lock-bolt, and 35 a plate for supporting the same, of a slideable rotatable controller having a recess adapted to receive the lock-bolt when retracted, a spring between said bolt and plate, and an independent non-rotatable 40 plunger for moving said controller longitudinally, and frictional interlocking means between said plunger and controller.

5. The combination with a lock-bolt, and 45 a plate for supporting the same, of a slideable rotatable controller having a recess adapted to receive the lock-bolt when retracted, a spring between said bolt and plate, and an independent non-rotatable plunger for moving said controller longitudinally, 50 and a rib-and-groove connection between the ends of said plunger and controller for fric-

tionally positioning the controller rotatively relatively to the plunger.

6. The combination with a stationary door plate disposed on one side of a door 55 and having a tubular extension, and a stationary door handle disposed on the other side of said door, of a lock-bolt, means for normally retracting said lock-bolt, a controller movable in said extension and having a recess adapted to receive said lock-bolt, a plunger supported in said handle for moving said controller longitudinally, a pull-knob on the plate-side of the door, and means for connecting said pull-knob and 60 controller for longitudinal movement to bring said recess into register with said lock-bolt.

7. The combination, with a stationary door plate disposed on one side of a door 70 and having a tubular extension, a stationary door handle disposed on the other side of said door, and means for interlocking said plate and handle, of a normally retracted lock-bolt, a controller movable in said extension and having a recess adapted to receive said lock-bolt, a plunger slidably and 75 non-rotatably supported in said stationary handle and for moving said controller longitudinally, a rotatable knob on the plate-side of the said door, and means for connecting said controller and knob for co-rotation and longitudinal movement.

8. The combination with a lock-bolt, and 80 a plate for supporting the same, of a slideable rotatable controller having a recess adapted to receive the lock-bolt when retracted, a spring between said bolt and plate, and an independent non-rotatable plunger for moving said controller longitudinally, and frictional interlocking means 85 between said plunger and controller, said controller having an extension supported in said plunger and adapted to be rotated by a key.

In testimony whereof I affix my signature in presence of two witnesses.

CARL DENZLER.
